W. P. ALBERT

CONTROLLING SYSTEM

Filed June 17, 1922

Inventor:
Walter P. Albert
by W. E. Beatty, Atty.

UNITED STATES PATENT OFFICE.

WALTER P. ALBERT, OF EAST ORANGE, NEW JERSEY, ASSIGNOR TO WESTERN ELECTRIC COMPANY, INCORPORATED, OF NEW YORK, N. Y., A CORPORATION OF NEW YORK.

CONTROLLING SYSTEM.

Application filed June 17, 1922. Serial No. 568,948.

To all whom it may concern:

Be it known that I, WALTER P. ALBERT, a citizen of the United States, residing at East Orange, in the county of Essex, State of New Jersey, have invented certain new and useful Improvements in Controlling Systems, of which the following is a full, clear, concise, and exact description.

This invention relates to electrical controlling mechanisms and more particularly to controlling mechanisms of the character employed in automatic and semi-automatic telephone exchange systems.

The object of the invention is an improved impulse controlling mechanism arranged to receive electrical impulses of current transmitted over a line or other circuit.

In accordance with this object a particular feature of the invention relates to an arrangement in which an impulse receiving relay is provided with an operating winding and a winding for opposing said first winding to prevent the relay from operating, together with means for rendering the opposing winding ineffective.

Another feature relates to an arrangement in which the impulse relay delivers impulses to a receiving device, wherein a third winding for said relay becomes effective at each operation and assists the operating winding to render said opposing winding ineffective, thus maintaining the relay operated until the impulse is fully delivered to said receiving device.

These and other features of the invention will become more clearly apparent from the following detailed description and also from the appended claims.

In Fig. 1 of the drawing there is illustrated an electrical control mechanism adapted for use in a telephone system of the character in which electrical impulses are transmitted over a line and recorded on register devices. Fig. 2 illustrates one of the control relays. While the invention is particularly well suited to mechanisms of this character, it will be understood that in its broadest aspects, it may be applied to a wide variety of purposes.

The drawing illustrates a subscriber's telephone line 102, 103 entering a central office. In any well known manner this line may be extended through a line finder or

a line switch either to a trunk leading to 55 a selector switch or to an operator's position. Inasmuch as the line extending means forms no essential part of this invention, the same has not been illustrated in the drawing.

Since it is desirable to take a record of the impulses transmitted over the line there is provided at the central office an impulse receiving and registering apparatus. This apparatus comprises, among other elements, 60 a plurality of relays 106, 108 and 109 which receive the incoming impulses and deliver them to the registers. There may be any desired number of registers for receiving the impulse series and, moreover, these registers 65 may be of any suitable form. Two registers 110 and 115 are shown, each consisting of a step-by-step switch driven by stepping magnets 117 and 119. As many other registers as are needed may be provided. In 70 addition to the registers a control switch 120 is employed for associating the impulse receiving mechanism in succession with the several register switches in order that each 75 succeeding series of impulses may be directed to a different register for registration.

It is often desirable to provide a plurality of these impulse receiving and recording mechanisms at the office, any one 85 of which may be associated with the incoming line. To this end a selecting switch, the brushes 104 and 105 of which are illustrated, is employed for finding an idle mechanism.

A detailed description will now be given of the manner in which the system operates. When the subscriber of line 100 initiates a call, the line is extended through brushes 104 and 105 of the selector switch to an idle 90 impulse receiving and recording equipment. A circuit may thereupon be traced from battery, through the left-hand winding of relay 108, left-hand winding of relay 106, brush 105, conductor 102, over the loop of 95 the calling line 100, conductor 103, brush 104, left-hand winding of the balancing coil 107 to ground. The relay 108 becomes energized in this circuit and attracts its armature. The relay 106 is so constructed that 100 current flowing through the left-hand winding in the direction indicated sets up a magnetic flux which assists the armature of the

relay to retain its normal position. If the relay is already released the left-hand winding of relay 106 tends to hold it released, while if the relay is in an operated condition, the action of this winding tends to cause the relay to release. Assuming the relay at this instant to be in a deenergized condition, the closure of the circuit above traced energizes the left-hand winding of relay 106 and the armature is held against its back contact, as shown.

Relay 108, upon operating, closes a circuit from ground, through its armature and front contact, right-hand winding of relay 108, middle winding of relay 106, conductor 122, resistance 114, to battery. This circuit through the middle winding of relay 106 may be also traced to battery in shunt of the resistance 114, by way of conductor 122, brush 111, terminal 123, contact of stepping magnet 117, conductor 121, to battery. Thus, the middle winding of relay 106 is fully energized. This middle winding sets up a magnetic flux which of itself would attract the armature of the relay on to its front contact. However, the flux through the left-hand winding of the relay opposes that of the middle winding and is sufficiently strong to prevent the armature from attracting to its front contact. The apparatus remains in this condition following the closure of line 100 until the subscriber transmits the first series of impulses.

The right-hand winding of relay 106 when energized is designed to establish a magnetic flux which aids the middle winding in holding the armature against the front contact. In other words, the middle winding and the right-hand winding together are sufficiently strong to overcome the effect of the left-hand opposing winding to hold the armature attracted against the front contact.

When the subscriber manipulates his dial 45 101 to send the first series of impulses, the line circuit is opened at the beginning of the first impulse. Immediately that the line is opened the left-hand winding of relay 106 deenergizes, and the circuit above traced 50 through the middle winding of said relay obtaining, this middle winding is free to operate the armature against its front contact. Immediately that the armature encounters the front contact, a circuit is established from ground, through the armature and contact of relay 108, armature and front contact of relay 106, right-hand winding of relay 106, conductor 122, resistance 114, to battery. In a similar fashion 55 60 to that above explained, this circuit, through the right-hand winding of relay 106, may also be traced to battery in shunt of the resistance 114 by way of conductor 122, brush 111, terminal 123, contact of stepping magnet 117 and conductor 121. Since the re-

sistance is removed from the circuit traced, the right-hand winding of relay 106 sets up a flux sufficiently strong to aid the middle winding of said relay in overcoming the effect of the left-hand winding. That is to say, should the line circuit again close to energize the left-hand winding of relay 106, this winding would be completely overcome by the cooperative effect of the middle and right-hand windings, so that the armature of the relay would remain operated against the front contact until such time as the relay has completed its function in delivering the impulse to the register mechanism.

Relay 106, in operating, also establishes a circuit from ground through the armature and front contact of relay 108, armature and front contact of relay 106, winding of the slow-to-release relay 109, brush 112, terminal 125, winding of the stepping magnet 117 to battery. The stepping magnet 117 now energizes and actuates the stepping pawl of the switch in its forward stroke preparatory to advancing the brushes of the register switch 110 forward one position.

In the disclosure the register 110 is shown as having but a single brush 116, while register 115 has a single brush 118. Obviously these registers may be equipped with as many sets of brushes as is necessary. The register switches 110 and 115 and control switch 120 are designed so that the brushes are stepped forward to the next set of terminals at the deenergization of the stepping magnets.

The slow-to-release relay 109, which also operates, completes a circuit from ground through its contact, winding of stepping magnet 113 to battery. Stepping magnet 113 of the control switch 120 energizes and prepares the stepping pawl to advance the brushes 111, 112, etc. forward to the second position when the circuit of said magnet is opened.

As soon as the magnet 117 is thoroughly energized and the stepping mechanism is advanced to its full forward stroke ready to release the brushes to their next position, the contact of said magnet 117 opens. The opening of this contact removes the shunt around the resistance 114 so that this resistance is now included in series with the circuits traced for the middle and right-hand windings of relay 106. The inclusion of resistance 114 decreases the current through the middle and right-hand windings of relay 106, but these windings are still sufficiently strong to hold the armature of the relay attracted provided the line circuit is still open and the left-hand winding of the relay deenergized.

The inclusion of the resistance 114 in series with the right-hand winding of relay 108, however, decreases the current through this winding to such an extent that the relay

begins to release its armature. The relay 108 does not release immediately, but requires an interval of time following the insertion of resistance 114.

5 When the line 100 closes again at the end of the transmission of the first impulse, the left-hand winding of relay 106 is energized and since the middle and right-hand windings are weakened due to the inclusion of 10 resistance 114 in their circuits, the said left-hand winding overcomes the other two windings and causes the relay to release its armature. The relay 106 opens the circuit of the stepping magnet 117 and said magnet releases 15 permitting brush 116 of the register 110 to step to its next position. Relay 108 which maintained its armature attracted during the releasing interval following the inclusion of resistance 114 in series with its 20 right-hand winding is now held through the reclosure of the circuit including its left-hand winding and the subscriber's line. Relay 109 being slow-to-release also holds its armature attracted to maintain the energization of the stepping magnet 113.

For each succeeding impulse of the first series transmitted over the subscriber's line, the relay 106 operates and releases in the manner explained and the stepping magnet 30 117 advances brush 116 of the register 110 from one position to another. At the end of the impulse series, the line circuit closes and relay 106 releases its armature to open the circuit of magnet 117 and relay 109. 35 Relay 109 after an interval becomes deenergized and opens the circuit of the stepping magnet 113. The magnet 113 releases and advances the brushes of the control switch 120 to their next position-terminals.

40 When the next series of impulses is transmitted the relay 106 operates on the first opening of the line and circuits are closed for the stepping magnet 119 of the second register 115 in a manner analogous to that 45 explained for the register 110. The only difference is that the control switch 120 is standing with its brushes 111 and 112 upon the second position-terminals 124 and 126.

For each of the several impulses of the 50 second series, brush 118 of the register 115 is advanced from position to position under the control of the relay 106. At the end of the series the control switch 120 is moved to a succeeding position where other register switches may be positioned if necessary.

When the mechanism is no longer required, the impulsing circuit is opened in any well known manner sufficiently long to permit relay 108 to release. Relay 108 at its 60 back contact closes a circuit which, in any well known manner, may effect release of the control switch 120 and the registers 110, 115.

What is claimed is:

1. The combination with a line and means 65 for transmitting a series of impulses there-

over, of a relay responsive to each succeeding impulse of the series having a winding for actuating the same, means opposing said winding to prevent the actuation of said relay, and means made active upon the actuation of said relay for overcoming the effect of said opposing means. 70

2. The combination with a line and means for transmitting a series of impulses thereover, of a relay responsive to each of said 75 impulses having a winding for actuating the same, means opposing said winding during the impulses to prevent the actuation of said relay, and means made active upon the actuation of said relay for overcoming the 80 effect of said opposing means.

3. The combination with an impulse circuit, of a relay responsive to each succeeding impulse of a series of impulses in said circuit having a winding for actuating the 85 same, means acting in opposition to said winding to hold said relay in its released condition, and means made active upon the actuation of said relay for overcoming the 90 effect of said opposing means.

4. The combination of a line and means for transmitting a series of impulses thereover, of a relay responsive to each of said 95 impulses having a winding for said relay for actuating the same, a second winding opposing said first winding to prevent the actuation of said relay, and means made active upon the actuation of said relay for overcoming the effect of said second winding.

5. The combination with a circuit and 100 means for transmitting impulses thereover, of a relay responsive to said impulses having a winding for said relay for actuating the same, a second winding opposing said first winding to prevent the actuation of said relay, and a third winding rendered effective under certain conditions to assist said first winding in overcoming the effect of said 105 second winding.

6. The combination with a circuit and 110 means for transmitting impulses thereover, of a relay responsive to said impulses having a winding for actuating the same, a second winding opposing said first winding to prevent the actuation of said relay, a third winding effective upon the actuation of said relay for assisting the first winding in overcoming the effect of said second winding, and a device actuated in response to each 115 operation of said relay.

7. The combination with a line and means for transmitting impulses thereover, of a relay responsive to said impulses having a winding for actuating the same, a second winding opposing said first winding to prevent the actuation of said relay and tending to cause the release of said relay when actuated, means rendered effective upon the actuation of said relay for assisting the first 125 winding in overcoming the effect of said 130

second winding, and a progressively operable device actuated upon each operation of said relay.

8. The combination with a line and means for transmitting impulses thereover, of a relay responsive to said impulses having a winding for actuating the same, means opposing said winding to prevent the actuation of said relay, means made active upon the

actuation of said relay for assisting the first winding in overcoming the effect of said opposing means, a device actuated upon each operation of said relay, and means controlled by said device for rendering said opposing means effective.

In witness whereof, I hereunto subscribe my name this 16th day of June A. D., 1922.

WALTER P. ALBERT.
